COMBINATION STORING AND DISPLAY FOOD TRAY

Ralph S. Zebarth, Kansas City, Mo., assignor, by mesne assignments, to Gordon Johnson Company, Kansas City, Mo., a corporation of Missouri

Filed Feb. 25, 1959, Ser. No. 54,740

Term of patent 14 years

(Cl. D58—12)

Fig. 1.

Fig. 2.

Fig. 3.

Fig. 4.

Fig. 5.

Fig. 6.

Fig. 1 is a top plan view of a combination storing and display food tray, showing my new design;

Fig. 2 is a side elevational view thereof;

Fig. 3 is a bottom plan view thereof;

Fig. 4 is an enlarged, perspective view thereof;

Fig. 5 is an end elevational view of the forwardmost end thereof illustrated in Fig. 4; and

Fig. 6 is an end elevational view of the opposite end thereof.

I claim:

The ornamental design for a combination storing and display food tray, as shown.
